FIGURE TOY

Willie Lewis Pryor, Waugh, Va.

Application October 22, 1936, Serial No. 107,094

2 Claims. (Cl. 46—120)

The present invention relates to new and useful improvements in figure toys and has for its primary object to provide, in a manner as hereinafter set forth, an article of this character which, when in operation, will closely simulate two men sawing a log of wood.

Another very important object of the invention is to provide, in a figure toy of the aforementioned character, novel means for reciprocating the representation of a saw and for actuating the figures connected thereto.

Still another very important object of the invention is to provide a figure toy of the character described embodying novel means for swinging one of the legs of the figures upwardly and rearwardly as the bodies of said figures move forwardly with the saw.

Other objects of the invention are to provide a figure toy of the character set forth which will be comparatively simple in construction, strong, durable, compact, light in weight, highly amusing, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views and wherein:

Figure 1 is a view in side elevation of a figure toy constructed in accordance with the present invention.

Figure 2 is a top plan view thereof.

Figure 3 is a vertical sectional view taken substantially on the line 3—3 of Figure 1.

Figure 4 is a vertical sectional view taken substantially on the line 4—4 of Figure 2.

Figure 5 is a detail view in perspective, showing the means for raising one of the legs of each figure as the body thereof swings forwardly.

Figure 6 is a detail view in elevation of the spring motor.

Figure 7 is a detail view in elevation of the mechanism driven by the spring motor for oscillating the shaft which reciprocates the saw.

Figure 8 is a detail view showing the means for anchoring one of the legs of the figures to the base.

Referring now to the drawings in detail, it will be seen that the embodiment of the invention which has been illustrated comprises an elongated base 1 of suitable material which is provided with a raised, transversely extending intermediate portion 2. The raised intermediate

portion 2 is substantially trough-shaped and fixed therein is a tube 3 representing a log. The log 3 is provided with end closures 4 and 5. Adjacent one end the log 3 is further provided with aligned openings 6, the purpose of which will be presently set forth.

Mounted on the end wall 5 of the log 3 is a spring motor which is designated generally by the reference numeral 7. A winding key 9 is provided for the spring 9 of the motor 7, said winding key extending rotatably through the end wall 5. The spring motor 7 further includes a suitable frame 10, a train of gears 11 mounted in the frame 10 and driven by the spring 9, etc. The gear 11 which is remote from the spring 9 is fixed on a crankshaft 12 as illustrated to advantage in Figure 3 of the drawings.

The reference numeral 13 designates a shaft which is rotatably mounted in the log 3, one end of said shaft being journaled in the end wall 4, the other end of said shaft extending through and being journaled in a bracket 14 which is mounted on the frame 10. A pinion gear 15 is fixed on this end portion of the shaft 13.

A stud 16 is fixed in the bracket 14 below the shaft 13. Threaded into one end of the stud 16 is a screw 17 on which a substantially triangular metallic plate 18 is mounted for oscillation.

The lower end portion of the plate 18 has formed therein a vertical slot 19 (see Figure 7) in which the throw of the crankshaft 12 is engaged. At its upper end, the plate 18 is provided with a horizontal flange 20 from which a segmental gear 21 depends for engagement with the gear 15. The reference numeral 22 designates a gear which is fixed on the shaft 13 at an intermediate point. The construction and arrangement is such that the shaft 13 will be oscillated by the spring motor 7.

Extending slidably through the openings 6 in the log 3 is a rack bar 23 representing a saw blade the teeth 24 of which are in mesh with the gear 22. The saw 23 further includes upstanding handles 25 on its ends.

The reference numeral 26 designates generally figures of suitable material which are mounted on the base 1 on opposite sides of the log 3. The figures 26 are preferably representations of men and each figure comprises a stationary leg 27 fixed on the base 1. Referring to Figure 8 of the drawings, it will be seen that the lower ends or foot portions of the stationary legs 27 are provided with lateral flanges 28 fixed to the base 1, as by welding or soldering, as at 29. Each figure 26 further includes a body 30 which is pivotally

mounted for swinging movement in a vertical plane on the upper portion of the stationary leg 27, as at 31. Arms 32 are pivotally connected, at one end, to the upper portions of the bodies 30 and at their other ends to the saw handles 25. Pivotally suspended from the bodies 30 are swinging legs 33 which are adapted to be raised by projections 34 which extend angularly from the lower portions of said bodies as best seen in Figure 10 of the drawings.

It is thought that the operation of the invention will be readily apparent from a consideration of the foregoing. The spring motor 7 is, of course, wound through the medium of the key 8 and released. The spring motor 7 drives the crankshaft 12 through the train of gears 11 and said crankshaft oscillates the plate 18 on its pivot 17. Of course, when the plate 18 is thus actuated the segmental gear 21 on said plate oscillates the shaft 13. Oscillation of the shaft 13 with the gear 22 thereon moves the saw 23 back and forth through the openings 6 of the log 3. As the saw 23 reciprocates in this manner the body portions 30 of the figures 26 are swung in a vertical plane 25 on their pivots 31 on the stationary legs 27 thereby closely simulating two men in the act of sawing wood. As the bodies 30 move forwardly the projections 34 engage and raise the swinging legs 33 thereby furthering the simulation. The swinging legs 33 are adapted to swing downwardly by gravity as the body portions 30 of the figures 26 return to an upright position.

It is believed that the many advantages of a figure toy constructed in accordance with the present invention will be readily understood, and although a preferred embodiment of the device is as illustrated and described, it is to be understood that changes in the details of construction and in the combination and arrangement of parts 35 may be resorted to which will fall within the scope of the invention as claimed.

What is claimed is:—

1. A figure toy of the class described comprising an elongated base including a raised, substantially trough-shaped transversely extending intermediate portion, a tube mounted on said raised portion and representing a log, said tube being closed at its ends and having aligned openings therein at an intermediate point, a spring 45 motor mounted in the tube on one of the end

walls thereof, said spring motor including a frame, a bracket mounted on said frame, a shaft journaled in said bracket and in the other end wall of the tube, a plate mounted for swinging movement on the bracket, said plate having a slot 5 therein, a crankshaft driven by the spring motor and engaged in the slot for oscillating the plate, a substantially segmental gear on the plate, a gear on the shaft driven by the first named gear, a gear fixed on the shaft at an intermediate point, 10 a rack bar extending slidably through the openings and engaged with the last named gear for reciprocation thereby, said rack bar representing a saw, and animated figures mounted on the base on opposite sides of the tube and connected to the 15 ends of the saw for actuation thereby.

2. A figure toy of the class described comprising an elongated base including a raised, substantially trough-shaped transversely extending intermediate portion, a tube mounted on said 20 raised portion and representing a log, said tube being closed at its ends and having aligned openings therein at an intermediate point, a spring motor mounted in the tube on one of the end walls thereof, said spring motor including a frame, a bracket mounted on said frame, a shaft journaled in said bracket and in the other end wall of the tube, a plate mounted for swinging movement on the bracket, said plate having a slot 25 therein, a crankshaft driven by the spring motor and engaged in the slot for oscillating the plate, a substantially segmental gear on the plate, a gear on the shaft driven by the first named gear, a gear fixed on the shaft at an intermediate point, 30 a rack bar extending slidably through the openings and engaged with the last named gear for reciprocation thereby, said rack bar representing a saw, animated figures mounted on the base on opposite sides of the tube and connected to the 35 ends of the saw for actuation thereby, each figure 40 including a stationary leg fixed on the base, a body pivotally mounted on the upper portion of the stationary leg for swinging movement in a vertical plane, an arm connecting the body to the saw for actuation thereby, a swinging leg pivotally 45 suspended from the body, and means on the body engageable with the swinging leg for elevating same as the body is swung forwardly.
